UNITED STATES PATENT OFFICE.

RAY H. MANSON, OF ELYRIA, OHIO, ASSIGNOR TO THE DEAN ELECTRIC COMPANY, OF ELYRIA, OHIO, A CORPORATION OF OHIO.

CONVEYANCE AND SIGNALING APPLIANCE THEREFOR.

1,048,557.

Specification of Letters Patent. Patented Dec. 31, 1912.

Original application filed April 24, 1911, Serial No. 622,858. Divided and this application filed September 18, 1911. Serial No. 649,964.

To all whom it may concern:

Be it known that I, RAY H. MANSON, a citizen of the United States, residing at Elyria, in the county of Lorain and State of Ohio, have invented certain new and useful Improvements in Conveyances and Signaling Appliances Therefor; and I do hereby declare the following to be a full, clear, and exact description of the invention, such as will enable others skilled in the art to which it appertains to make and use the same.

My invention relates to alarm signaling devices for conveyances, such as automobiles, boats, etc., and to improvements in such devices and the systems thereof, my general object being to produce in such a device, a system and apparatus associated therewith which will meet the requirements of modern use upon such conveyances.

Another object of my invention is the production of a signal device controlling means in which a device for modifying the energy delivered to the signal device is employed and in which such modifying device is preferably mounted in a dust proof, water proof casing with signal controlling means and both mounted in a convenient place preferably upon the steering wheel.

Other objects of my invention will appear from the particular description following.

While the invention itself will be best understood by reference to such description when taken in connection with the accompanying illustration showing a specific embodiment thereof, the scope will be more particularly pointed out in the appended claims.

This application is a division of my application 622,858, filed April 24, 1911.

Figure 1 is a perspective view of a portion of a conveyance showing the signal device in combination therewith. Fig. 2 is a plan view of the circuit controller casing and contents. Fig. 3 is a cross section taken along one axis of the device shown in Fig. 2. Fig. 4 is a section taken along an axis at right angles to the axis upon which Fig. 3 is taken. Fig. 5 is a diagram of the circuit connections used.

Referring now to the drawings, a conveyance is shown at 1. Means for controlling the steering of this conveyance is employed and in Fig. 1 is shown as a steering post 2, upon which is mounted a steering wheel 3.

I have shown a steering wheel, though any well known form of steering device may be substituted therefor. The signal device proper is shown at 4 carried upon the conveyance and in Fig. 1 is shown as a horn, preferably an electrically controlled horn. A dust proof, water proof casing 5 is mounted upon a conveyance, preferably upon the steering wheel, as shown in Fig. 1.

Means for controlling the signal device 4 are mounted upon the conveyance, preferably housed inside the casing 5. In the form shown this controlling device consists of a switch S controlled by a push button P, which when mounted upon the steering wheel enables the driver to control the signal device with the pressure of the thumb and without detracting his attention from the road in front of him or from the operation of the conveyance. The controlling device S and the signal device 4 are associated by connecting means 6, here shown as circuit connectors 7 and 8.

In order that the apparatus which I have invented may be a success, it is highly important that the apparatus should be so constructed as to be readily placed upon cars which are already in use. I provide in the circuit a current modifying device X here shown as a resistance device, preferably a non-inductive resistance. I also provide a casing 5 which is secured by a bracket 61 and screws 62 to some part of the conveyance, preferably as shown in Fig. 1, to the steering wheel. A cover 60 is fastened upon the top of the casing 5 by screws 63 making the same dust proof and water proof. The circuit controller S which consists of switch springs 64, 65 and 66 controlled by the push button P, is mounted upon the inside of this casing. In order that the current modifying device X may be protected from moisture and dust, in order that it may be readily installed with the rest of the apparatus, upon the machine, and in order that it may be readily accessible, I mount it with the circuit controller S inside the casing 5. An entering port 70 and channel 71 are shown in the walls of the casing 5 through which the connecting means 6 enter the casing. Contact terminals 72 are provided on the inside of this casing for the conductors 7 and 8. At 73 I show a clamp for securing the terminals of these conductors in-

side the casing so as to remove the strain from the terminals 72.

At B is shown a source of electric current for supplying energy to the magnet 40.

5 The special features and advantages which I have shown in this application and which constitute my invention herein disclosed, enable me to produce apparatus of the character described which is superior in 10 these features to the devices of this class now in use. I have overcome many objectionable features to those which are now in use and have added to the convenience of these devices both in the installation and in 15 the use thereof. Hitherto it has been difficult to install devices of this kind upon conveyances and to make such installation secure enough to prevent the dislodging of the apparatus by the vibrations of the machine. I 20 have provided apparatus which may be installed by simple means upon conveyances of the character described and when so installed will be so securely mounted thereon, that the vibrations of the machine will not 25 disturb the same.

While I have shown this particular form of my invention and these particular forms of the details thereof, it will be obvious to those skilled in the art that numerous and 30 extensive departures from the form and details of the apparatus here shown may be made without departing from the spirit of the invention, the same being herein shown in this form solely for the purpose of clearly 35 illustrating one specific embodiment thereof.

I claim:

1. In a device of the class described adapted to be used upon the steering wheel of a vehicle, the combination of a flat cylindrical casing formed from a single sheet of metal and having an opening in the side thereof, a conduit stud inserted in said opening, an insulating bushing in said stud, a top for said casing having an opening in

the center of said top, the edge of the top 45 about the opening being turned upward to form an annular boss around the opening serving as a guide, a push button in said opening guided by said boss, an annular boss on the side of said button and at the 50 bottom thereof adapted to engage the underside of the opening in the top, three contact springs for controlling an electric circuit mounted upon the bottom of said casing and controlled by said push button, one of 55 said springs forcing said push button upward until the boss upon the button engages the under side of the edge of the opening in the top, a resistance device mounted in said casing adjacent said contact springs 60 and having its terminals connected to two of said springs and means for connecting said casing to a steering wheel.

2. In a device of the class described, adapted to be used upon the steering wheel 65 of an automobile, the combination of a flat cylindrical casing having an opening in the side thereof through which electric conductors may be led into the casing, a top for said casing having an opening therein, a 70 boss around said opening, a push button mounted in said opening and having a boss formed around its side near the bottom to engage the underside of the top around the opening, three contact springs mounted in 75 said casing and controlled by said push button, a resistance device mounted upon the bottom of said casing and having its terminals connected to two of said springs, and means to connect said casing to the steering 80 wheel of an automobile.

In testimony whereof, I affix my signature in the presence of two witnesses.

RAY H. MANSON.
